(57) **CLAIM**

The ornamental design for a scent generator as shown and
described.

DESCRIPTION

FIG. 1 is a front, top, right perspective view of a scent
generator showing our new design;

FIG. 2 is a front, bottom, left perspective view thereof;

FIG. 3 is a front elevational view thereof;

FIG. 4 is a rear elevational view thereof.

FIG. 5 is a left side elevational view thereof; and

FIG. 6 is a right side elevational view thereof;

FIG. 7 is a top plan view thereof; and

FIG. 8 is a bottom plan view thereof.

FIG. 9 is a partially enlarged left side elevational view
thereof along the lines 9-9 and 13-13 of FIG. 5;

FIG. 10 is a partially enlarged right side elevational view
thereof along the lines 10-10 and 14-14 of FIG. 6;

FIG. 11 is a partially enlarged bottom plan view thereof
along the lines 11-11 and 15-15 of FIG. 8; and,

FIG. 12 is another partially enlarged bottom plan view
thereof along the lines 12-12 and 16-16 of FIG. 8.

The broken lines illustrating portions of the scent generator
form no part of the claimed design. The single dot-dash
broken lines defining boundaries of the claimed design form
no part of the claimed design. The double dot-dash broken
lines showing perimeters of partially enlarged portions of
the drawings form no part of the claimed design.
